UNITED STATES PATENT OFFICE.

ALVIN R. MARTINE, OF CLEVELAND, OHIO, ASSIGNOR TO A. R. MARTINE COMPANY, INC., OF NEW YORK, N. Y., A CORPORATION OF DELAWARE.

SAVINGS BANK.

Application filed September 27, 1922. Serial No. 590,778.

The present invention relates to a coin container or safe which is more particularly adapted to be embodied in a construction that is portable and may be made in such size that it may be handily carried in the pocket of a user wherein coins of a given denomination may from time to time be deposited by the user.

One of the objects of the invention is to provide a safe in which the coin shall be visible, but which shall be so arranged that in a given size of pocket safe, which size will be convenient to be inserted in the pocket of the user, a maximum number of 15 coins of a given denomination may be inserted.

Reference should be had to the accompanying drawings forming a part of the specification, in which Fig. 1 is a perspective view showing a construction of safe embodying my invention; Fig. 2 is a longitudinal sectional elevation of the showing in Fig. 1; Fig. 3 is a transverse sectional elevation of the showing in Fig. 1; Fig. 4 is a 25 top plan view of a portion of the pocket safe construction; Fig. 5 is an elevation of the end in which coins may be inserted.

Referring to the drawings, 1 represents a body portion which may be made up in any desired manner, but will consist of a top face 2, a bottom face 3, and side portions 4 and 5. This body portion may be made up out of a single piece of metal, or it may be made up of a plurality of pieces of metal.

In what we will term the top surface 2 there will preferably be provided a plurality of slots 6 which extend longitudinally, and there will be as many slots as there will be rows of coins, all of which will be later explained. On the reverse side or upon the face 3 of the safe there will be also a plurality of openings, which will directly align with the opening 6 which has before been explained.

Co-operating with the body 1 is a structure by which the interior of the safe is divided into three compartments, so that there is a partition member which extends longitudinally of the body portion 1, and beneath the thin strip of metal between the adjacent opening 6, which body portions may be indicated at A, B and C. These compartments may be formed in a variety of ways, but in the present construction I have shown 55 a preferred form which consists in provid-

ing a slidable member that may be introduced inside of the body member 1, and which will serve as a sort of tray for carrying the coins, and which will serve to remove the coins when the tray is removed 60 from the body portion 1.

In the form as shown the tray consists of a member 8 which has two portions 8^a and 8^b, which lie in the same general plane, and a rectangular raised portion which is indicated at 8^c. The portions 8^a and 8^b will slide upon the inside of the side member 3 while the portion 8^c will slide upon the inside of the side member 2, and the portion 8^c lying between the portions 8^a and 8^b will 70 co-operate with the central slot 6, and the slot in the member 3 which is directly below it, and the same will be true with respect to the parts 8^a and 8^b.

The portion 8^c will be formed with a slot 75 9 while the portions 8^a and 8^b will also be formed with a slot 10 and 11 respectively, so that when the slide member thus described is assembled with respect to the member 1 the various slots which are in 80 alignment will provide a complete view through the bank, and when the coins are inserted in the bank the coins will be visible within the bank when viewing the same from either the side member 2 or the side 85 member 3.

It will also be apparent that upon the insertion of the slide member the chambers A, B and C are defined by the upstanding walls which are at the edges of the portions 8^c, 8^a and 8^b, so that the chambers A and C 90 may be said to be on one side of the safe, while the chamber B is on the other side of the safe.

Secured to the member 8^a is a slanting member 12, and a similar member 12^a is secured to the member 8^b, and a third similar member 12^b is secured to the member 8^c, but it slants in a direction at an angle with respect to the members 12 and 12^a. These 95 members are provided in order to cause coins which are inserted, as will be later explained, to assume a diagonal position within the respective chambers A, B and C.

At the end of the sliding member there 105 is a head 13 which is secured thereto, and it is provided with spring members 14 and 15, and there is also a similar spring member 16 on the opposite side which are adapted to be compressed when the sliding mem- 110

ber is inserted within the body portion 1 and then released so that they occupy the slots 17 and 18 in the side member 2 of the body portion, and the spring member 16 occupies a similar slot in the side member.

Adjacent each of these springs 14, 15 and 16, there is an opening such as shown at 19 of Fig. 1, through which a suitable tool may be inserted to depress the springs so that the slidable member may be withdrawn from the body member 1.

At the other end of the body member there is a member 20 which is permanently secured at the end of the body portion, and it is provided with a series of slots such as indicated at 21, there being a slot for each compartment formed within the body portion of the safe, and each of these slots is so arranged with respect to a compartment within the safe that coins inserted in any given slot will be deposited only in that compartment with which it cooperates.

Within the member 20 there is a spring-like detent 22 which co-operates with each of the openings 21 so as to prevent the dropping out of coins which have once been inserted through the slot 21.

The compartments will be formed of a width and depth to accommodate a series of coins of a given denomination. That is to say, the slots may be of a width to accommodate dimes or nickels or any other predetermined coin. The height or depth, as it may be termed, of each compartment, will be such as to permit the overlapping of a plurality of coins when they are in a diagonal position within the compartment. For instance, as shown in Fig. 2, the coin 23 when inserted through the slot 21, will drop to the bottom of its compartment, and will engage with the member 12 and assume a diagonal position, such as shown, and subsequent coins which are inserted through the slot 21 will pile up in the fashion shown in Fig. 2.

Coins may be continually inserted all of which will assume the diagonal position until the compartment is entirely filled up.

It will be seen that coins which are inserted in the compartments A and C will occupy relatively similar diagonal positions, while coins that are inserted in the compartment B will occupy what might be termed an opposite diagonal relation. But in all instances the coins in a given compartment will occupy diagonal position, and each coin will be overlapping with respect to the coin or coins which are adjacent to it.

This feature of construction permits a relatively large number of coins to be inserted in a given compartment so that a bank of comparatively small dimensions will be able to accommodate a comparatively large number of coins.

I am aware that there are at present on the market certain pocket savings banks in

which the coins which are inserted in a given compartment of the safe touch edge to edge, and therefore the number of coins which may be inserted in such a compartment is relatively small, but in the present construction by having a pocket safe of the same length but a little greater in thickness, it is possible to greatly increase the number of coins which may be inserted within a compartment of the safe.

Having described my invention, I claim:—

1. A savings bank container comprising an outer body portion having an opening at one end and provided with a transverse slot near the open end, a slidable member which is adapted to be inserted within said body portion, a resilient inclined member secured at one end to the base of the slidable member and provided with a laterally extending lug at the opposite end thereof, a cover member secured to the slidable member and adapted to enclose the open end of the body member, the lug on the resilient inclined member adapted to engage the transverse slot in the body portion and to securely lock 90 said body portion and slidable member together when in closed position.

2. A savings bank container comprising an outer body portion having an opening at one end, a slidable member adapted to be inserted within said body portion, a cover member secured to one end of said slidable member and adapted to enclose the opening in the body portion, resilient means carried by the slidable member for locking 100 said member with respect to the body portion, and means for receiving a coin, provided in the body portion opposite the open end thereof.

3. A savings bank container comprising an outer body portion having an opening at one end, a slidable member adapted to be inserted within said body portion comprising a plate bent to form a series of compartments extending the entire length of 110 the container and further arranged so that the base of the central compartment engages the body portion on the opposite side to the base of the outer compartments, each compartment having a width corresponding to 115 the diameter of the desired coin to be deposited, a cover member secured to one end of said slidable member and adapted to enclose the opening in the body portion, means carried by the slidable member for locking 120 said member with respect to the body portion, and separate means communicating with each compartment for receiving coins.

4. A savings bank container comprising an outer body portion having an opening at 125 one end and provided with a transverse slot near the open end, a slidable member which is adapted to be inserted within said body portion and provided with independent compartments, a resilient inclined member for 130

- each compartment secured at the lower end to the base of the slidable member and provided with a lug at the opposite end thereof, said members being so positioned that the 5 coins when deposited are required to lie in an inclined position without interfering with the resilient member as a locking means, a cover member secured to the slidable member and adapted to enclose the open end of the 10 body member, and a lug on the resilient inclined member adapted to engage the transverse slot in the body portion and to securely lock said body portion and slidable member together in closed position.
- 15 5. A savings bank container comprising an outer body portion having an opening at both ends, slots in the broad surfaces thereof and diametrically opposite, transverse slots at one end of said body portion, a slidable 20 member comprising a plate bent to form a series of compartments extending the entire length of the body portion when in closed position, slots in the base portion of the sliding member corresponding and registering 25 with the slots in the body portion, a cover member secured to one end of the slidable member and adapted to close an opening in the body portion, a resilient inclined member secured at the lower end of the base of 30 each compartment of the slidable member and provided with a lug at the opposite end thereof, said lug adapted to engage the transverse slots in the body portion when in closed position, means for disengaging the
- lug from the transverse slots, a cover for 35 the opposite end of the body portion provided with slots communicating with each compartment to permit the reception of coins, and a spring member secured to the under side of said cover extending over the 40 slots to maintain the coins within the compartments.
6. A savings bank container comprising a body portion, a slidable member which is adapted to be inserted within said body portion said slidable member having means which when associated with the body portion provide, a plurality of separate compartments, each compartment having an opening adjacent one end through which coins may be inserted, said slidable member being provided with slanting members adjacent the end thereof opposite that into which the coins are inserted there being one slanting member associated with each compartment when the sliding member and body portion are assembled each of said compartments being of a width substantially the same as the diameter of a particular coin and each compartment being of a transverse dimension which is greater than the thickness of a coin whereby the coins may assume a diagonal overlapping position within the said compartments.
- In testimony whereof, I hereunto affix my 55 signature.

ALVIN R. MARTINE.
